UNITED STATES PATENT OFFICE.

JAMES L. BALDWIN, OF CHICAGO, ILLINOIS.

PACKAGE ELEVATOR.

Application filed November 8, 1926. Serial No. 147,072.

This invention relates to package elevators and carriers especially adapted for use in stores, factories and other structures.

Briefly stated, an important object of this invention is to provide a package carrier which is entirely mechanical except for the motive source and in which the necessity of remote control switches for the electric motor and the wiring incident to the employment of remote control switches are avoided.

A further and equally important object is to provide a package carrier having novel means whereby the simultaneous operation of the same from the various stations is made an impossibility and in which the carrier may be controlled from any station and caused to stop at the proper stations.

Other objects and advantages will be apparent during the course of the following description.

In the accompanying drawing forming a part of this application and in which like numerals are employed to designate like parts throughout the same,

Figure 1 is a perspective view illustrating the control and supporting means for the carrier;

Figure 2 is a side elevation of the structure shown in Figure 1;

Figure 3 is a horizontal sectional view taken on line 3—3 of Figure 2;

Figure 4 is a perspective view of a carrier and the supporting means therefor;

Figure 5 is an elevation of the upper portion of the apparatus;

Figures 6 is a detail elevation of the motor-switch operating unit as assembled;

Figure 7 is a perspective view of an elevator shaft and the various closures therefor;

Figure 8 is a plan view of an automatic door closure embodied in the invention and by means of which the attempted operation of the elevator by more than one person is prevented.

In the drawings, the numeral 5 designates a table mounted on legs 6. Figure 1 clearly illustrates that a pair of standards or guide rods 7 are secured to the table by suitable means and as is obvious extend upwardly to the floors or stations to which service is to be provided.

Referring now to Figure 4, it will be seen that the standards 7 are engaged by guide rollers carried by brackets 9, the brackets

being secured to the elevator or movable receptacle 10. The brackets 9 are arranged in pairs at opposite sides of the receptacle 10 and provide means whereby the receptacle is permitted to partake of an easy vertical movement under the influence of gravity and a lifting mechanism consisting of a continuous chain 14.

The chain 14 is trained about an overhead support and has connection with a centrifugal clutch 16 by which power is transmitted from an electric motor 18 to the chain. More specifically, the electric motor drives a counter shaft 20 upon which the centrifugal clutch 16 is operated. The centrifugal clutch 16 is of a type which brings about the gradual driving engagement between the motor and the chain and in fact the driving connection between these parts is not completed until the motor attains a predetermined speed. Since the specific construction of the clutch forms no part of this invention, it has not been illustrated in detail, but it might be added that the clutch may be of the type illustrated in my copending application Serial No. 3,470, filed Jan. 19, 1925. It will be seen that when the motor 18 is energized the continuous chain 14 will be operated to raise the receptacle 10. Figure 4 illustrates that the chain is connected to the receptacle 10 by a pair of arms 22. The arms 22 extend horizontally from the receptacle and have connection in any preferred manner with the chain. That part of the chain between the upper and lower arms 22 is preferably taut.

Further reference to Figure 4 will show that a rod or other support 30 is connected to and is extended between the upper and lower arms 22 and carries a pair of attaching sleeves 32 upon which stop dogs 34 are pivotally mounted. The stop dogs 34 are urged outwardly to operative position by coil springs 36 so that when the same are engaged with one of a series of laterally projecting cranks 40 on a control rod 41, the receptacle or carriage 10 will be brought to a halt.

In further explaining the relation between the dogs 34 and the crank 40, it might be said that the outer surfaces of the dogs 34 are curved inwardly toward their attaching portions to define cam surfaces against which one of the cranks 40 may be engaged to push one of the dogs inwardly preparatory

to the entrance of the crank into the space between the dogs. Figure 4 clearly illustrates that when the carriage approaches one of the cranks 40 the dog 34 nearest thereto will be moved inwardly and the other dog will be employed as a retainer by which the carriage is brought to a halt.

Attention is directed to the fact that the sleeves 32 are backed by coil springs 44 mounted on the rods 30 and forming cushions for use when the carriage is brought to a halt.

One of the cranks or stops 40 is located at or adjacent each station and if it is desired to bring the carriage to a halt at one of the floors, possibly the second floor, the crank or stop 40 at the second floor is positioned so that it is in the path of travel of a longitudinally curved leaf spring cam 50 carried by one of the sleeves 32. Thus when the carriage approaches the floor at which it is to stop the leaf spring cam 50 engages the crank 40 and moves the same laterally a limited distance for a purpose to be herein-after described and for the obvious purpose of properly presenting the same to the cam surface of the dog 34 nearest the crank.

If there are four floors the four cranks 40 may be spaced about 90 degrees apart and, of course, one crank is located at each floor as previously suggested.

Coming now to the control means for the motor and to the means for causing the carriage to stop at the required floor or station, attention is invited to Figures 1, 2 and 3, particularly Figure 1 which illustrates that a collar 60 may be rigidly mounted on the control rod 41 and is provided with a radial extension 62 having a pivoted dog 64.

Reference to Figure 1 will clearly show that the dog 64 is adapted to cooperate with a series of lugs 66 on a switch operating member in the nature of a loose collar having a radial arm 68. One side edge of the radial arm 68 is beveled to define cam adapted to press a roller 70 into one of the depressions 72 of a disk shaped member 74 rigidly secured to and movable with the rod 41. The depressions 72 correspond in number to the number of stations and to the number of lugs 66, and the arrangement is such when one of the cranks 40 is positioned to stop the carriage 10, one of the depressions 72 will be positioned to receive the roller 70. The roller 70 is adapted to be pressed down into the adjacent depression 72 as previously suggested. When this occurs the motor 18 is energized.

Figure 1 illustrates that the roller 70 is mounted on a branch 80 of a bell crank. The bell crank is fulcrumed to a standard or bracket 82 and is provided with a depending branch 84, the lower terminal of which has connection with the toggle arms 86 of an electric switch 87.

Thus when the roller 70 is forced down into one of the depressions 72 by the cam like arm 68 the bell crank will be operated to turn on the switch. As long as the roller 70 is held in one of the depressions 72 the motor will continue to operate and raise the carriage. As suggested, this action is induced by the movement of the rod 41—in the direction indicated by the arrow in Figure 6—through the agency of the dog 64 in bearing against one of the lugs 66 with which the cam arm 68 is integral. For purposes of clearness, the latter has been shown remote from the roller 70 in Figures 1, 2 and 3, but its true position is shown in Figure 6.

Figure 6 shows the true position of the switch actuator, full lines indicating the positions of its parts when the current is cut off, and finely-dotted lines when it is turned on. It should now be borne in mind that the rod 41 carries both the collar 60 and the disk-shaped member 74 rigidly thereon, and that the dog 64 has a predetermined position in relation to the depression 72 opposite it. With this position noted, it will be seen that with the depressions 72 spaced—by degrees—as the collar lugs 66, the relation between the dog and any further depression will be in equal multiple. As to the roller 70, its position may be considered fixed, except for its short vertical movement, since its connection by arm 80 to standard 82 makes it a stationary element, laterally considered. Therefore, when the rod 41 is turned in the direction of the arrow (Figs. 1 and 6), it will carry the dog 64 so as to bear against the next lug 66 in its path. This movement will push along the arm 68 and cause the roller 70 to be displaced in a downward direction into the depression 72 below, so that the actuation of the switch is accomplished, the parts appearing as per finely dotted lines in Figure 6.

Since the depressions 72 are spaced as the lugs 66, according to previous mention, it will be seen that whatever the location of the dog 64 in the rotary travel of the rod 41, its impulse in the direction described will accomplish the closing of the switch. The rod 41 may be turned in the opposite direction without affecting the dog 64, as the latter will then slip the lugs 66. The reverse motion of the rod 41 will, however, effect the opening of the switch, by causing the rear wall of the depression 72 to impinge on the roller 70 in the manner of a cam and crowd the same back into elevated position. In order that this motion may not push the arm 68 away from a position handy to the roller 70, the said arm is extended with a guard flange 91 over the roller which prevents its separation therefrom. Also, the arm 68 is extended radially with a depending flange 92 which strikes the end of the bell crank 130

branch 80 and stops the arm when the stroke of the latter in working direction is forced or sudden.

It is now evident that the rod 41 may be turned in the free direction to properly position the crank 40 corresponding to a selected station, this consisting in the location of the same in the path of travel of the leaf cam 50. A short twist or turn of the rod in the working direction (see arrows) will now set the motor in motion to elevate the carriage. Thus when the carriage approaches the station at which it is to stop the leaf cam 50 will engage the crank 40 and turn the rod back so as to again open the switch stopping the motor. The carriage 10, of course has sufficient upward inertia to continue its upward movement until member 40 engages dogs 34. Thus no further movement will be imparted to the carriage until the apparatus is again set.

The rod 41 may have a pinion 94 at each station and each pinion is engaged by a second pinion 96 on an adjusting shaft 98.

Figure 3 illustrates that the shaft 98 may be provided with a selector wheel 100 which may be manually operated to position the particular crank 40 corresponding to the station desired at one of the stations in the path of travel affected by the leaf cam 50.

In carrying out the invention the table 5 may be provided with a suitable number of cushioning elements consisting of rods 110 upon which cushioning and rebound springs 112 and 114, respectively, are mounted. Of course, the cushioning springs 112 are mounted above the table and the rebound springs which are somewhat weaker than the cushioning springs are mounted below the table.

The carriage has connection with a sprocket chain 118 clearly shown in Figure 4, for attachment of a counter balancing weight (not shown) so that the motor is relieved of the necessity of lifting the entire weight of the carriage and the contents of the same. It is preferred to have the carriage slightly heavier than the counter balancing weight so that the descent of the carriage when empty is assured. A suitable governor friction device or brake 119 may be employed to retard the descent of the carriage. When the carriage is descending to a desired floor or station the motor need not be operated.

The attempted simultaneous operation of the elevator by persons at different stations is prevented by the provision of the structure illustrated in Figures 7 and 8, wherein it is shown that a shaft or casing 120 encloses the carriage and associated parts and is provided with a plurality of doors 124 by means of which access to the carriage is made possible. Referring to Figure 8, it will be seen that each door 124 is provided with an inwardly extending bracket or arm 126, the terminal of which has a shoulder or

head 128 adapted to be engaged by the branches 130 and 132 of a bell crank rigidly secured on a shaft 140 extending for the full length of the stations.

When one of the doors 124 is opened the head 128 will engage the branch 130 so that the shaft 140 is turned in a counter clockwise direction and the branches 132 at the other stations positioned in retaining engagement with the lugs 128 so that the other doors are held against opening. In this latter position the branches 130 rest against stops 130^a thus holding branches 132 at right angles to the shouldered door-carried arms 126. Obviously when one door 124 has been opened the engagement of the headed arm ends 28 of the other doors will engage their respective branches 132 and the doors will be held shut.

When the door previously opened is closed the head 128 engages arm 130 and swings the same clockwise and connecting rod 140 is automatically returned to a position which will permit the opening of any one of the other doors.

Having thus described the invention, what is claimed is:

1. An elevator comprising a support, a carriage slidably connected to the support, dogs mounted on said carriage, a movable stop adapted to be positioned between said dogs, and a cam adapted to turn said stop and position the same in the path of travel of one of said dogs, each of said dogs being provided with a cam surface in the path of travel of said stop.

2. An elevator comprising a support, a carriage slidably connected to the support, dogs carried by said carriage, a movable stop adapted to be positioned between said dogs, a cam adapted to turn said stop and position the same in the path of travel of one of said dogs, each of said dogs being provided with a cam surface in the path of travel of said stop, and a power element having connection with said carriage.

3. An elevator comprising a support, a carriage slidably connected to the support, dogs carried by said carriage, a movable stop adapted to be positioned between said dogs, a cam adapted to turn said stop and position the same in the path of travel of one of said dogs, each of said dogs being provided with a cam surface in the path of travel of said stop, a power element having connection with said carriage, and means connecting said power element and said stop.

4. An elevator comprising a support, a carriage slidably connected to the support, arms carried by the carriage, dogs between said arms, a movable stop adapted to be positioned between said dogs, a cam adapted to turn said stop and position the same in the path of travel of one of said dogs, each of said dogs being provided with a cam surface in the path of travel of said stop, a power

- element having connection with said carriage, means connecting said power element and said stop, and cushioning devices between said dogs and said arms.
5. An elevator comprising a carriage, a pair of dogs associated with said carriage and being pivotally supported, a stop member adapted to be engaged between said dogs, a cam movable with the dogs and adapted 10 to move said stop member laterally directly into the path of travel of one of said dogs, springs means urging the dogs to operative positions, a motor having a power transmitting member connected to said carriage, control means for said motor, and a control 15 rod supporting said stop member and having connection with said motor.
6. An elevator including a carriage, a control rod having stops for engaging and holding 20 said carriage, a motor having a power transmitting element for operating said carriage and a switch, a switch controlling device, a plate having connection with said rod with seating means to hold said switch 25 controlling device in an extreme position.
7. An elevator including a carriage, a control rod having stops for engaging and holding 30 said carriage, a motor having a power transmitting element for said carriage and a switch, a switch controlling device, a member having rigid connection with said rod with seating means to hold said switch controlling device in one position, and cams to urge said switch controlling 35 device to another position.
8. An elevator comprising a control rod having a stop, a radial arm mounted on said rod and having a cam surface, a member rigid with said rod and having depressions, a switch controlling device adapted to be received in one of said depressions, the cam surface of said radial arm being adapted 40 to urge said switch controlling device into one of said depressions and temporarily hold the same therein.
9. An elevator comprising a control rod having a stop, a radial arm mounted on said rod and having a cam surface, a member rigid with said rod and having depressions, a switch controlling device adapted to be received in one of said depressions, the cam surface of said radial arm being adapted 45 to urge said switch controlling device into one of said depressions and temporarily hold the same therein, and a carriage having means adapted to be engaged by said stop.
10. An elevator comprising a control rod having a stop, a radial arm mounted on said rod and having a cam surface, a member rigid with said rod and having depressions, a switch controlling device adapted to be received in one of said depressions, the cam surface of said radial arm being adapted 50 to urge said switch controlling device into one of said depressions and temporarily hold the same therein, a carriage having means adapted to be engaged by said stop, and means on said control rod for impelling said radial arm.
11. An elevator comprising a carriage, a control rod having a stop adapted to cooperate with the carriage, a motor having a power transmitting member connected to said carriage, a switch for said motor, a switch controlling device consisting of a bell 75 crank, one branch of which is connected to said switch, the other branch of the bell crank being adjacent to said rod, and a cam operated by said rod and adapted to urge the second named branch of the bell crank 80 to a position to close said switch.
12. An elevator comprising a carriage, a control rod having a stop adapted to cooperate with the carriage, a motor having a power transmitting member connected to 85 said carriage, a switch for said motor, a switch controlling device consisting of a bell crank, one branch of which is connected to said switch, the other branch of the bell crank being adjacent to said rod, a cam operated by said rod and adapted to urge the second named branch of the bell crank to a position to close said switch, and a member mounted on said rod and having means to receive a portion of the second named 90 branch of said bell crank.
13. An elevator comprising a carriage, a motor having a power transmitting member for said carriage, said motor also being provided with a switch, a control rod having a plurality of stops arranged at various points, holding means carried by the carriage and adapted to be engaged by said stops, a switch controlling device associated with said rod, and means carried by said carriage to engage the stop and turn the rod to actuate 100 said switch control device when the carriage reaches a predetermined point.
14. A control for an oscillatory switch lever comprising a rod, a uni-directional impeller carried by the latter, a collar loose on the rod and having abutments selectively engageable by the impeller when the rod is turned to correspond, a radial arm integral with the collar and adapted to depress the switch lever on the occasion of an impulse, and a member rigid on the rod and having a cam to raise the switch lever when the movement of the rod is reversed.
15. A control for an oscillatory switch lever comprising a rod, a uni-directional impeller carried by the latter, a collar loose on the rod and having a circumferential series of abutments selectively engageable by the impeller when the rod is turned to correspond, a radial arm integral with the collar and adapted to depress the switch lever on the occasion of an impulse, and a member rigid on the rod and having a circumferential series of cams corresponding in number 120
- 125
- 130

to the said abutments, that cam which is nearest the switch lever serving to raise the latter when the movement of the rod is reversed.

5 16. A control for an oscillatory switch lever comprising a rod, a uni-directional impeller carried by the latter, a collar loose on the rod and having abutments selectively engageable by the impeller when the rod is turned to correspond, a radial arm integral with the 10 collar and adapted to depress the switch lever on the occasion of an impulse, and a member rigid on the rod and having a cam to raise the switch lever when the movement of the rod is reversed, said arm having an extension to retain it in proximity to the switch lever.

17. An elevator comprising a vertically-slidable carriage driven by a motor, said motor being provided with a switch, a control rod having a plurality of stops spaced along the rod as the stations intended for the carriage and also distributed circumferentially to correspond, dogs carried by the carriage and engageable by said stops, a cam carried by the carriage, to engage a given stop and move the same into the path of the dogs, such movement causing the rod to turn, an oscillatory lever for actuating the switch, a 25 uni-directional impeller carried by the rod,

a collar loose on the rod and having a series of abutments corresponding to the number of stops on the rod and selectively engageable by the impeller when the rod is turned to correspond, a radial arm integral with the 35 collar and adapted to depress the switch lever on the occasion of an impulse, and a member rigid on the rod and having a circumferential series of cams corresponding in number to the said abutments, that cam 40 which is nearest the switch lever serving to raise the latter when the movement of the rod is induced by the first mentioned cams in a direction reverse to that induced by the impeller. 45

18. An elevator comprising a support, a carriage slidably connected to the support, dogs mounted on said carriage and a movable stop adapted to be positioned between said dogs. 50

19. An elevator comprising a support, a carriage slidably connected to the support, dogs mounted on said carriage, a movable stop adapted to be positioned between said dogs, and a cam adapted to turn said stop 55 and position the same in the path of travel of one of said dogs.

In testimony whereof I affix my signature.

JAMES L. BALDWIN.
